UNITED STATES PATENT OFFICE

147,506

DESIGN FOR A FELT BOOT

Arthur E. Pfeiffer, Worcester, Mass.

Application March 11, 1947, Serial No. 137,507

Term of patent 3½ years

(Cl. D7—7)

To all whom it may concern:

Be it known that I, Arthur E. Pfeiffer, a citizen of the United States and a resident of Worcester, in the county of Worcester and Commonwealth of Massachusetts, have invented a new, original, and ornamental Design for a Felt Boot, of which the following is a specification, reference being had to the accompanying drawing, forming a part thereof, in which:

Fig. 1 is a view in perspective of a felt boot, showing my new design, and

Fig. 2 is a similar view at a different angle.

I claim:

The ornamental design for a felt boot, substantially as shown.

ARTHUR E. PFEIFFER.
